RUG CORNER HOLDER

William H. Porter, Northport, N. Y., and Clarence M. Porter, Lakeside, Pt. Clair, Quebec, Canada

Application April 15, 1940, Serial No. 329,678

5 Claims. (Cl. 154—49)

This invention relates to new and useful improvements in a rug corner holder.

The invention proposes the use of a flexible stiff strip in combination with the corner of a rug, and mechanism for releasably attaching the strip to the rug, whereby the corner is stretched and held down.

More specifically, the pair of outwardly directed pointed elements are mounted on the ends of said strip and adapted to engage the material of the rug for attaching the strip to the rug.

Still further the invention contemplates a modification wherein the flexible strip is formed from two sections adjacent each other, and a means is provided for slightly extending and retracting these sections relative to each other, whereby the pointed elements may be better engaged with the material of the rug.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a rug corner holder constructed in accordance with this invention.

Fig. 2 is a fragmentary plan view of a rug with the corner holder applied.

Fig. 3 is a sectional view taken on the line 3—3 of Fig. 2.

Fig. 4 is a plan view of a rug corner holder constructed in accordance with a modified form of the invention.

Fig. 5 is a fragmentary sectional view taken on the line 5—5 of Fig. 4.

Fig. 6 is a similar view to Fig. 1 but illustrating another form of the invention.

The rug corner holder includes a flexible stiff strip of material 10, preferably flexed spring steel, adapted to engage radially from the corner 11^a of a rug 11. A pair of outwardly directed pointed elements 12 are mounted on the ends of the strip 10 and are adapted to engage the material of the rug for stretching the corner of the rug and holding it down. These pointed elements 12 have vertical stem base portions 12^a connected with the material of the strip 12, and outwardly extending horizontal portions 12^b. These latter portions are formed with the points.

The operation of the device is as follows:

The strip 10 is slightly flexed and then the pointed elements 12 are engaged into the material

of the rug 11. The strip 10 is then released and straightens out, moving outwards the pointed elements 12 which thus firmly anchor themselves into the material of the rug.

In Figs. 4 and 5 a modified form of the invention has been disclosed which distinguishes from the prior form in the fact that the corner holder includes a flexible stiff strip 10' formed from a pair of adjacent sections 10^a and 10^b. These sections have their adjacent end portions overlapping as clearly shown in Figs. 4 and 5. The outer ends of the sections 10^a and 10^b are provided with the outwardly directed pointed elements 12. The overlapping ends of the sections 10^a and 10^b are associated with means for retracting and extending the sections relative to each other.

The means mentioned in the previous paragraph includes a stud 14 relatively mounted on one of the overlapping end portions, namely, the end portion of the section 10^a, and having an eccentric circular portion 14^a rotatively engaged in the other of the overlapping end portions. A flange 14^b is permanently mounted upon the free end of the stud 14. Another flange 14^{bb} is formed upon the free end of the eccentric portion 14^a. This flange 14^{bb} is disposed within a circular recess formed in the end of the section 10^b. A rectangular recess 15 is formed in the outer face of the eccentric portion 14^a engageable by the end of a screw driver or other turning tool. One of the overlapping sections is provided with projecting elements 16 engaging in corresponding niches in the adjacent section for holding the sections 10^a and 10^b in end alignment with each other.

The operation of this form of the invention is as follows:

A screw driver is engaged in the opening 15 and the stud 14^a is turned, and simultaneously the sections 10^a and 10^b are slightly flexed to disengage the projecting portions 16 from their niches, so that the sections 10^a and 10^b are moved towards each other. The rug holder is then placed upon the bottom of a rug and slightly flexed so that the pointed elements 12 slightly engaged into the material of the rug. Then a screw driver is placed in the recess 15 and the stud 14^a is turned to cause the sections 10^a and 10^b to be moved outwards relative to each other back to their original positions, as illustrated in Fig. 5. This extends the sections 10^a and 10^b and forces the pointed elements 12 securely into the material of the rug and so anchors the holder in position.

In Fig. 6, the pointed elements 12' are made integral with and stamped out from the strip 10''

and the bottom face of the strip 10" is covered with a rubber sheet 17 to prevent slipping of the device on the floor.

It is to be understood that the strips and pointed elements may be of any desired size and shape.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new and desire to secure by United States Letters Patent is:

1. In a rug holder of the class described, a flexible stiff strip, a pair of outwardly directed pointed elements, mounted on said strip and engageable into the bottom face of said rug for maintaining said strip in position on the bottom face of said rug, said strip being formed of separate sections having their adjacent ends overlapped, and means for securing said overlapped ends together in a manner to be extended to increase the overall length of said strip and so prevent said pointed elements from becoming disengaged from said rug.

2. In a rug holder of the class described, a flexible stiff strip, a pair of outwardly directed pointed elements, mounted on said strip and engageable into the bottom face of said rug for maintaining said strip in position on the bottom face of said rug, said strip being formed of separate sections having their adjacent ends overlapped, and means for securing said overlapped ends together in a manner to be extended to increase the overall length of said strip and so prevent said pointed elements from becoming disengaged from said rug, comprising a stud rotatively extended through an opening in one of said sections, an eccentric formed on said stud and engaging an opening in the other end of said sections.

3. In a rug holder of the class described, a flexible stiff strip, a pair of outwardly directed pointed elements, mounted on said strip and engageable into the bottom face of said rug for maintaining said strip in position on the bottom face of said rug, said strip being formed of separate sections having their adjacent ends overlapped, and means for securing said overlapped ends together in a manner to be extended to

increase the overall length of said strip and so prevent said pointed elements from becoming disengaged, from said rug, comprising a stud rotatively extended through an opening in one of said sections, an eccentric formed on said stud and engaging an opening in the other end of said sections, and a recess formed in said eccentric and engageable by a tool for turning the same to successively extend and retract said sections.

4. In a rug holder of the class described, a flexible stiff strip, a pair of outwardly directed pointed elements, mounted on said strip and engageable into the bottom face of said rug for maintaining said strip in position on the bottom face of said rug, said strip being formed of separate sections having their adjacent ends overlapped, and means for securing said overlapped ends together in a manner to be extended to increase the overall length of said strip and so prevent said pointed elements from becoming disengaged from said rug, comprising a stud rotatively extended through an opening in one of said sections, an eccentric formed on said stud and engaging an opening in the other end of said sections, and means for holding said sections against relative movement when in the completely extended position.

5. In a rug holder of the class described, a flexible stiff strip, a pair of outwardly directed pointed elements, mounted on said strip and engageable into the bottom face of said rug for maintaining said strip in position on the bottom face of said rug, said strip being formed of separate sections having their adjacent ends overlapped, and means for securing said overlapped ends together in a manner to be extended to increase the overall length of said strip and so prevent said pointed elements from becoming disengaged from said rug, comprising a stud rotatively extended through an opening in one of said sections, an eccentric formed on said stud and engaging an opening in the other end of said sections, and means for holding said sections against relative movement when in the completely extended position, comprising projections formed on one of said sections and engageable with complementary recesses formed in the other of said sections.
